UNITED STATES PATENT OFFICE.

CARL A. PEDERSEN, OF WILSON, ARKANSAS.

STOVEPIPE-FASTENER.

1,230,321.

Specification of Letters Patent. Patented June 19, 1917.

Application filed March 6, 1917. Serial No. 152,671.

To all whom it may concern:

Be it known that I, CARL A. PEDERSEN, a citizen of the United States, residing at Wilson, in the county of Mississippi, State 5 of Arkansas, have invented certain new and useful Improvements in Stovepipe-Fasteners; and I do hereby declare the following to be a full, clear, and exact description of the invention, such as will enable others skilled 10 in the art to which it appertains to make and use the same.

This invention relates to an improved means for retaining a stove pipe within a flue opening and for securing the pipe collar 15 in proper position.

The principal object of the invention is to provide means of this character which is of an extremely simple and inexpensive construction, and which may be quickly and 20 conveniently applied for the purpose of securing a stove pipe and collar in proper position with respect to the flue opening.

With the above and other objects of similar nature in view, the invention consists in 25 the construction, combination and arrangement of parts set forth in and falling within the scope of the appended claim.

In the drawing:

Figure 1 shows a transverse section 30 through a stove pipe in position in a flue opening, with the collar in position and the invention applied, and

Fig. 2 is a section taken on the line 2—2 of Fig. 1.

Referring now more particularly to the accompanying drawing, there is shown a portion of a wall 5, suitably provided with a flue opening 6. Removably engaged in the usual manner in the flue opening is a stove 40 pipe 7, provided at diametrically opposite points with apertures 8. A stove pipe collar of conventional type is engaged upon the

pipe 7 as is usual and is also provided at diametrically opposite points with apertures 9 alining with the apertures 8 in the pipe. 45 In order to retain the pipe within the flue opening and the collar in proper position therein, there are driven into the wall 5 at opposite sides of the pipe, screw eyes 10, the eyes of which are disposed in alinement with 50 the apertures 8 and 9. A straight length of wire 11 is then inserted through the screw eye 10 and through the alining apertures 8 and 9, the pipe and collar being in this manner securely held in place as is evident. 55 To facilitate the insertion and removal of the wire 11 one of its ends is bent as shown to provide a finger loop 12, while in order to prevent its accidental withdrawal, the opposite end thereof is bent at an angle close to 60 the adjacent screw eye 10.

It is evident from the foregoing that there has thus been provided a simple and inexpensive means for retaining a stove pipe and collar in proper relation to the flue opening, 65 and a means which may furthermore be applied with ease and convenience.

What I claim is:

In combination an apertured wall, a pipe 70 removably mounted therein and provided with diametrically opposite apertures, a collar surrounding the pipe provided with apertures alining with the apertures in the pipe, eye forming members secured in the wall at opposite sides of the pipe and in 75 alinement with the apertures, and a retaining member passed through said alining eyes and apertures.

In testimony whereof, I affix my signature, in the presence of two witnesses.

CARL A. PEDERSEN.
